UNITED STATES PATENT OFFICE.

JOSEPH E. TRAHAN, OF DETROIT, MICHIGAN.

SPARK-PLUG.

1,227,699.

Specification of Letters Patent.

Patented May 29, 1917.

Application filed September 5, 1916. Serial No. 118,322.

To all whom it may concern:

Be it known that I, JOSEPH E. TRAHAN, a citizen of the United States of America, residing at Detroit, in the county of Wayne 5 and State of Michigan, have invented certain new and useful Improvements in Spark-Plugs, of which the following is a specification, reference being had therein to the accompanying drawings.

- 10 This invention relates to spark plugs, and the primary object of my invention is to provide a spark plug with an automatic air intake valve which will permit of air passing through the spark plug and impinging against the terminal ends of the electrodes, to remove carbon, incrustations of foreign matter, lubricating oils and other matter that may accumulate or be deposited on the electrodes to interfere with sparking or jumping of current from one electrode to the other across the spark gap. In other words, the air delivered against the electrodes is adapted to maintain the same in a clean serviceable condition.
- 15 A further object of my invention is to furnish a spark plug with a simple, inexpensive and durable air intake valve which will be automatically opened when an engine cylinder takes fuel and closed when the engine cylinder exhausts gases or places fuel under compression.

20 A still further object of my invention is to provide a valvular construction that is applicable in various type of spark plugs, and the construction by which I attain the above and other objects will be hereinafter described and then claimed.

Reference will now be had to the drawings, wherein—

25 Figure 1 is a vertical sectional view of a spark plug provided with a valve in accordance with my invention;

Fig. 2 is a horizontal sectional view of the spark plug;

30 Fig. 3 is a similar view illustrating a slight modification of the same; and

Fig. 4 is a similar view of a further modification of the invention.

35 In the drawings, 1 denotes a spark plug body or socket having a fixed electrode 2. Mounted in the body 1 is a body of insulation 3 seated and retained in the body in the usual and well-known manner. On the top of the body of insulation 3 is a retaining

member 4 for a tubular exteriorly screw-threaded stem 5 provided with the nut 6 whereby electrical connections can be made with the spark plug in the ordinary manner. The tubular stem 5 has the bore 7 thereof in communication with the bore 8 of the body of insulation 3 to receive an electrode 9. The electrode 9 is retained in the body of insulation 3 by frictionally contacting with the walls of the bore 8, and as illustrated in Figs. 2 and 3, the bore may be cylindrical and the electrode rectangular in cross section, or the bore may be rectangular in cross section and the electrode cylindrical. In either instance, there are a plurality of conduits between the walls of the electrodes and the walls of the body of insulation and these conduits permit of air being drawn through the body of insulation to impinge against the terminals of the electrodes.

40 Mounted upon the upper end of the tubular stem 5 is a valve seat member 10 held against accidental displacement by a jam nut 11. The valve seat member 10 has an intake port 12 communicating with a valve seat 13 in said member. Loosely mounted in 45 the member 10 is a valve 14 having a rod 15, said rod extending in the tubular stem 5 to rest on the electrode 9, also to extend through the intake port 12 to permit of manual manipulation.

45 As shown in Fig. 1, the valve 14 is unseated, such being the position of the valve when an engine cylinder is receiving fuel. The suction or reduction of atmospheric pressure which draws the fuel into an engine cylinder will also draw a supply of air through the spark plug, in the form of a blast or jet, which will dislodge any matter adhering to the terminals of the electrodes. When the engine cylinder is exhausting gases or compressing fuel the valve 14 is automatically seated, but may be manually unseated when it is desired to blow out or clean the air passages of the spark plug.

50 As shown in Fig. 4, the valve rod 15 may have flat side walls providing clearance for the passage of air, and the electrode 9 may be similarly constructed.

55 It is thought that the utility of my invention will be apparent without further description and while in the drawing there is illustrated the preferred embodiments of my invention, it is to be understood that the

structural elements are susceptible to such variations and modifications as fall within the scope of the appended claim.

What I claim is:—

- 5 In a spark plug, a spark plug body provided with an electrode, a body of insulation carried by said spark plug body and having a cylindrical bore therethrough, an exteriorly screwthreaded stem mounted on
- 10 said body of insulation and having a bore aligning with the bore of the body of insulation, an electrode in the bore of said body of insulation extending into the bore of said stem and rectangular in cross section to provide air passages between said electrode and
- 15 said body of insulation and said stem, a dome shaped valve seat member screwed on said stem and provided with an air intake port and a valve seat around the inner end 20 of said port, a jam nut on said stem to hold

said valve seat member in an adjusted position, an automatic valve in said valve seat member, and a valve rod of less cross-sectional area than said electrode carried by said valve and having an end thereof below 25 said valve extending into the bore of said stem to rest on the electrode extending into said stem and the opposite end of said rod above said valve extending through the air intake port of said valve seat member and 30 loose therein to permit of manual adjustment of said valve between the upper end of said stem and the valve seat.

In testimony whereof I affix my signature in the presence of two witnesses.

JOSEPH E. TRAHAN.
